REVERSIBLE TARGET

Alvin W. Smith, Cincinnati, Ohio; John G. Robinson, administrator of said Alvin W. Smith, deceased, assignor to Emma L. Bauer, Cincinnati, Ohio

Application May 31, 1945, Serial No. 596,925

1 Claim. (Cl. 273—105.2)

1

This invention relates to improvements in movable targets primarily for military, police and civilian training and practice in the development of skill and accuracy for subduing an adversary in combat or hostile and belligerent.

The target, therefore, primarily is in placard form, outlined in plan in simulation of a human body from the neck to the limbs, preferably without arms suspendingly sustained from a trolley, for transporting in either of alternate directions and maneuvering in which the forward posture is positioned in the direction of travel.

An object of the invention is to provide an apparatus for sustaining and linearly conveying a target in alternate directions, quickly and easily erected for field or indoor range service, the target under an extended control from a safety point as at a suitable distance forward from the target.

Another object of the invention is to provide a movable target in plan having an outline in simulation of a human body, trolley suspended and transportable for transit in alternate directions and reversible for changing the direction of target transit and effectively controlled against displacement by heavy wind pressure.

Another object is to provide a plurality of targets sustained and moved in unity and correspondingly controlled by a controller operated by a single attendant for simultaneously servicing several shooters.

Various other features and advantages will be more fully set forth in the description of the accompanying drawings, in which:

Figure 1 is a plan elevation of the apparatus.

Figure 2 is an enlarged plan view of a pair of targets as a duplex unit in a position as shown in Figure 1.

Figure 3 is an enlarged section on line 3—3, Figure 2.

Figure 4 is a section on line 4—4, Figure 2.

Figure 5 is a front elevation similar to Figure 1 with the control lines omitted.

Figure 6 is a front elevation of a single target.

Figure 7 is an enlarged broken front elevation of a single target headed in a reverse direction from that shown in Figure 6.

Figure 8 is a section on line 8—8, Figure 6.

Figure 9 is a plan view of a modified form of stanchion to which the lower end of the target is clipped.

Referring to the drawings illustrating the apparatus of knock down and portable form for ready placement for field service, 1—1, indicates a pair of standards or vertical supports each 55

2

constituting a pair of relatively angular disposed posts or uprights connected at their upper ends with their lower ends resting upon or embedded into the ground. The standards, support and are connected by a span of a trolley wire or cable 2, connecting with the top ends of the standards and from the standards continue outwardly and downwardly therefrom in a guy extension to and for anchoring respectively to pegs 3, driven into the earth, securely bracing the standards and for tautly stretching the spanning section of the trolley wire. A base trolley wire 4, parallel with the spanning section of the upper trolley wire 2, and in alignment therewith in a taut and stretched condition, slightly elevated from the plane of the earth, has its opposite ends connected or attached respectively to the anchoring pegs 3. The lower trolley strand 4, intermediate of the standards, rests upon supports 5—5, bearing upon the earth's surface to stabilize the strand and maintain its active position at a determined spacing or elevation from the earth.

The trolley wire supporting structure is disclosed in a most simple form of knock down type for compact folding and portability adapted to be easily and quickly erected for field or other service, although other means may be employed for permanent field or other locations, it being obvious that various methods may be employed for tautly mounting a pair of suitably spaced and parallel trolley lines.

The upper horizontal trolley wire or cable 2, provides a track for a trolley or carriage 6, constituting a rod having a bracket or hanger 7, respectively fixed to each of its opposite ends and journaling a peripherally grooved roller for riding upon the trolley wire or cable 2. The rod for the carriage may be made in various lengths for sustaining either one or a plurality of targets 40 removably and adjustably clipped thereon and for selectively adjusting the relative spacing of a plurality of targets upon a single carriage.

A target 8, generally of a corrugated paper board material, in plan, is cut to an outline in simulation of a human body in standing or erect posture, presenting a fore edge 9, and a rear edge 10, and normally disposed and suspended vertically or perpendicularly from the carriage or trolley. A loose score or tally sheet is removably applied respectively over both the opposite face sides of the target for shooter identification and has appropriate diagram and scale indicia printed thereon. The top and bottom ends of the target are reinforced by a suitable binding. The top end of the target has a clip 11, removably clipped

or clamped thereto, the clip being connected to one end of a pliable or flexible strap 12, which correspondingly at its opposite end has attached thereto a second spring clip 11, for removable attachment to the rod 6, of the carriage or trolley. The clips 11, are of conventional construction, in general constituting a pair of opposing hinged jaws, spring urged for automatically moving the jaws toward each other and compressively binding and connecting to an element interposed between the jaws.

The lower end of the target is removably secured by a pair of spring clips 11-11, to the upper or head end of a stanchion 13, preferably of T-form, constituting a pair of spaced parallel bars or strips fixed at one end to a cross bar 14, to which the clips 11 are hingedly attached. The opposite or lower end of the stanchion carries a flat spring swivel snap 15, connecting with a roller hanger 16, engaged with the lower trolley wire or cable 4.

A radial arm 17, at its inner end is engaged between the vertical bars of the stanchion and pivotally connected thereto. The arm normally extends horizontally or angularly declined from the stanchion and in the direction of target travel, and provides the means for reversing or alternating the position of the target in a change in direction of travel. The forward end of the arm 17, connects with a pull rope or draw line for drawing and maneuvering the target, the line extending through an aperture in the arm and as illustrated in Figure 8, for a single target has its end attached or fixed to the end of a second radial arm disposed at right angles to the arm 17, and removably fixed to the stanchion. For a single target a pair of opposing draw lines 18-19, traverse the aperture through the forward end of the radial arm 17, and each from the arm extends therefrom at an angle in opposite directions and to relative opposite sides of the target and are respectively connected to the free end of an anchoring rod 20, fixed to the stanchion and extending at right angles or laterally relative to the opposite face sides of the target.

For duplex targets connected in unity, as shown in Figures 2 and 4, the forward ends of the stanchion radial arms 17, respectively of each target are connected by a tie rod 21, and the draw line for one direction of pull extends through the aperture of the stanchion arm of one target and is secured to the anchoring rod 20, thereof, while the opposing draw line for imparting a reverse direction of travel correspondingly connects with the stanchion arm and anchoring rod of a second target. From the target or targets the draw lines 18-19, extend relatively in opposite directions and are engaged about a grooved pulley of a pulley block 22, attached to a respective standard, and thence the lines are directed towards each other to a common tackle or windlass 23.

The structure of the windlass is optional and preferably of a type which can be conveniently carried by an operator, positioned from the target at a suitable distance therefrom for safety and non-interference to the shooter. In general, it embodies a pair of pulleys 24-24, unitarily in driving connection with a shaft operated by a crank handle 25. The draw lines are wound upon the respective pulleys in an arrangement which will provide for the winding of one while unwinding the other uniformly, the action alternately depending upon the direction of rotation of the crank handle. The operator arbitrarily controls the degree of tension or slack in the lines

by any slight change in his distance position from the target to meet the manipulating requirements and speed at which he elects to operate and avoid any snarling of the lines. It allows considerable latitude for the operator to vary the operating control and target manipulation through slight changes in his position. The target moves in a direction depending upon which of the draw lines is under winding tension, and the direction of target travel can be quickly changed and responsive by imposing tension from one to the other of draw lines.

Assuming that the winding tension is on the draw line 18, the directional force will move the radial arms of the targets in line therewith, bringing the front edge of the target coordinate- 15 ly to head in the direction of travel, in which instance the target would be moved or conveyed to the left. Imposing a drawing tension on the line 19, the position of the target will be imme- 20 diately reversed, exposing an opposite face side to the shooter as the radial arms, to extend in line with the direction of travel, would be pulled from one side to the other, reversing the position of 25 the target which is free to swing about due to the flexible connections, by means of the strap 12, to the trolley or carriage.

In Figure 6, the parts are shown in a position moving to the left, while in Figure 7, they are 30 reversed for moving to the right. The transit, its rate of speed, and maneuvering of the target are solely under the discretion of the operator, so that the shooter can be kept constantly un- 35 aware of target movement, and which can be governed to require high skill to meet a proper scoring within certain prescribed limits of time, and desired speed equal to the fastest of human movements.

The target, being guided at both its top and 40 bottom ends, at the top by a pair of spaced hangers and at the bottom by a single hanger or pulley block, is provided with extreme freedom in transit, permitting the same to be easily conveyed at an excessively high rate. The top and bottom connections hold the target erect 45 against extreme high wind pressures to which it may be exposed when positioned in an open field.

The double connection of the draw line with 50 the target through the radial arm and a relatively angularly disposed anchoring rod permits an operator to maintain a reversing control under severe wind pressure against which one alone may not be effective. The draw line connection between the radial arm and anchoring rod of a target is approximately taut and normally the radial arm alone would be effective for an appropriate reverse exposure of the target. Should, however, a face side, in making a shift, become 55 exposed broad side to the sharp or high wind pressure, there would be a tendency to advance the target in an askew position so that its control would be lost. Under such conditions the pulling stress is transferred to the rod disposed at an angle to the radial arm as from the rear 60 side of the target, imposing a twisting tendency thereto to bring the target beyond the broad side exposure to the wind and to a more or less wind deflecting position or beyond a controlling influence of the wind.

For a knock down feature the radial arm of 65 the stanchion is pivotally mounted to fold downward between and parallel with the bars and it is locked in its erected position by a wedge 26, 70 interposed between the inner end of the arm

and the top cross bar 14, of the stanchion and to which the wedge is tied. The anchoring rod is frictionally fitted into the head of the stanchion and, therefore, is readily removable therefrom.

In the modification shown in Figure 9, the wedge 26, is eliminated and the pivoted end of the arm 17, is outlined to swing and bind against the underside of the cross bar 14, when the arm is in an active position and preferably inclined from a horizontal plane, with the operating lines connected thereto as previously described.

Upon operation of the windlass or other form of power means, the target or targets can be traversed at will in either of alternate directions a desired rate of speed and under the complete control of the operator. A shift from one direction to a reverse can be instantly made at any point for the maximum length of target travel. It can be arrested at any point and drawn to a half-way condition to only expose the edge of the target to the shooter for a misshot.

The target, being clipped to its supporting devices, is readily replaceable for substitution to advancely apply a set of scoring sheets thereon.

Having described my invention, I claim:

A movable target, comprising a trolley line and a guy line in parallelism with the trolley line and determinately spaced therefrom, a trolley transmittingly mounted on said trolley line, a target interposed between said trolley and guy lines having its upper end in flexible and detachable connection with said trolley, a stan-

chion at one end removably connected to the lower end of said target and its opposite end in swiveled, detachable and transmitting connection with said guy line and having a plurality of radial arms extended therefrom, one in plane with the target and the other extending respectively from each of the opposite face sides of the target, and a tackle for translating the target on said trolley and guy lines in alternate directions from a remote point, having a pair of lines extended therefrom each respectively having an end portion extending along the trolley and guy lines from relative opposite ends thereof and in connection with said arm in plane with the target and an arm extending from the face side of the target to translate the target and expose the face side to which it connects to a shooting point.
